UNITED STATES PATENT OFFICE

96,484

DESIGN FOR A COMBINED RADIO LOUD-SPEAKER CABINET AND WALL SHELF

Delwin W. Kussman, Racine, Wis.

Application April 30, 1935, Serial No. 56,625

Term of patent 7 years

To all whom it may concern:

Be it known that I, Delwin W. Kussman, a citizen of the United States, residing at Racine, in the county of Racine and State of Wisconsin, have invented a new, original, and ornamental Design for a Combined Radio Loudspeaker Cabinet and Wall Shelf, of which the following is a specification, reference being had to the accompanying drawing, forming part thereof.

The single figure of the drawing is a view in perspective of a combined radio loudspeaker cabinet and wall shelf embodying my design.

I claim:

The ornamental design for a combined radio loudspeaker cabinet and wall shelf as shown.

DELWIN W. KUSSMAN.
